United States Patent Office

Des. 216,889

Patented Mar. 17, 1970

216,889

TELEPRODUCTION CONSOLE

Darrell S. Staley, Santa Clara, and Robert W. Bornschlegel, Mountain View, Calif., assignors to Ampex Corporation, Redwood City, Calif., a corporation of California

Filed Apr. 28, 1969, Ser. No. 16,918

Term of patent 14 years

Int. Cl. D14—02

U.S. Cl. D26—5

The figure is a front, top and left side perspective view of a teleproduction console showing our new design, the right side being a mirror image of the left; and the back, bottom and underside portions being conventionally plain.

We claim:

The ornamental design for a teleproduction console, substantially as shown and described.
